US0D1072034S

(12) **United States Design Patent** (10) **Patent No.:** **US D1,072,034 S**
(45) **Date of Patent:** **** Apr. 22, 2025**

(54) **EYEWEAR**

(71) Applicant: **100% Speedlab, LLC**, San Diego, CA (US)

(72) Inventors: **Ludovic Francis Boinnard**, San Diego, CA (US); **Marc Guy Blanchard**, Solana Beach, CA (US); **Jerome Jacques Marie Mage**, San Diego, CA (US); **Jamie D. Oman**, San Diego, CA (US)

(73) Assignee: **100% Speedlab, LLC**, San Diego, CA (US)

(**) Term: **15 Years**

(21) Appl. No.: **29/879,697**

(22) Filed: **Jul. 11, 2023**

Related U.S. Application Data

(63) Continuation of application No. 29/799,635, filed on Jul. 15, 2021, now Pat. No. Des. 996,512.

(57) **CLAIM**

The ornamental design for an eyewear, as shown and described.

DESCRIPTION

FIG. 1 is a perspective view of the new design for an eyewear;

FIG. 2 is a front view thereof;

FIG. 3 is a rear view thereof;

FIG. 4 is a left side view thereof, the right side view being the mirror image thereof;

FIG. 5 is a top view thereof; and,

FIG. 6 is a bottom view thereof.

The broken lines illustrate portions of the eyewear that form no part of the claimed design.

1 Claim, 6 Drawing Sheets
